BY

Harry Lea Dodson

ATTORNEY.

UNITED STATES PATENT OFFICE

HARLEY E. ANDERSON, OF KANSAS CITY, MISSOURI, ASSIGNOR TO GUSTIN-BACON MANUFACTURING CO., OF KANSAS CITY, MISSOURI, A CORPORATION OF MISSOURI

AUTOMATIC SLACK ADJUSTER

Application filed September 12, 1930. Serial No. 481,418.

My invention relates to an automatic slack adjusting device, and it has for its object to provide an improved structure constituting a connection between the usual horizontal cylinder lever and the live truck lever of a railroad car, of such a nature as to compensate for different thicknesses of brake shoes, and to maintain the proper length of said lever, under all conditions of use.

Further objects and advantages of the invention will be set forth in the detailed description which follows.

In the accompanying drawings:

Fig. 1 is a plan view,

Fig. 2 is a side elevation,

Fig. 3 a vertical sectional view of my improved take-up or slack adjuster,

Fig. 4 is a view, partly in side elevation and partly in section, of a modified form of the invention, and

Fig. 5 is a transverse vertical sectional view upon line 5—5 of Fig. 2.

Similar reference numerals refer to similar parts throughout the entire description.

The drawings show the usual horizontally movable cylinder lever 5 of a railroad car air brake, and the live truck lever 6, the movement of which applies or releases the brake shoe (not shown).

In the form of the invention illustrated in Figs. 1 to 3, the connection between the levers 5 and 6 comprises a two-part top rod, one part 7 of which is in the form of a rack bar having teeth 8 formed thereon, said part 7 of the top rod being pivotally connected to the live truck lever 6, at 9. The other part 10 of the top rod is pivotally connected to the cylinder lever 5, by a pin 11.

A main housing is provided, having an aperture therethrough in which the rack bar 7 slides, its movement being limited by means of a dog 22 mounted in a well 20 formed in the said main housing, said dog 22 engaging the teeth 8 of the rack bar 7, and being held normally in engagement therewith by means of a coil spring 24. The main housing is provided with an upwardly extending portion 15, which is provided with internal threads to which is fitted a threaded portion

14 of the rod 10, a nut serving to lock it in position.

The lower portion of the main housing is provided with a sleeve 16, in which is slidably mounted a telescoping sleeve 13 of an auxiliary housing, a coil spring 17 serving to hold the sleeve 13 normally projected. Adjacent the outer end of this sleeve 13 is formed a well 19, in which is mounted a dog 21, which is held normally in engagement with the ratchet teeth 8 on the rack bar 7, a coil spring 23 serving for this purpose.

The well 19 has an upwardly extending portion, provided with two apertures, through the lower of which the rack bar 7 slides. The upper aperture 12 permits the auxiliary housing to slide upon the top bar 10 which forms a guide therefor, and also prevents the top rod 10, from sagging when the brakes are in released position.

A fixed stop bracket 25 is secured to the car (not shown) in position to be engaged by the wall of the well 19, in such manner as to thrust the telescoping sleeve 13 of the auxiliary housing to the left and cause its dog 21 to engage in the next tooth 8 of the rack bar 7.

When it is desired to apply new shoes, the top rod is disconnected at the cylinder lever 5 and the rod 10 is turned a quarter turn. This turns the housing assembly on the rack bar 7, and the rod and housing are pulled forward until it strikes the cotter pin stop 18. The rib 30 on the rack makes it necessary for the car repairer to turn the rod 10 back like he found it, thereby resetting the dogs 21 and 22 to mesh properly with the teeth 8 on the rack bar 7.

Upon restoring the parts to their former position, the dogs 21 and 22 will be initially engaged with the teeth 8 of the rack bar 7 with which they happen to align, but it is apparent that when the top rod 10 is drawn to the right, and the face of well 19 strikes the stop bracket 25, the dog 21 will be brought to rest, and any further movement of rod 10 towards the right will result in causing the next succeeding tooth or teeth 8 of the rack bar 7 to pass over and be engaged by the dog 21, the spring 17 being compressed in this action. When the force tending to move

rod 10 to the right is released, the spring 17 will act to thrust the dog 22 to the left, to engage succeeding teeth 8 of the rack bar 7, and thus an automatic take-up of undesirable slack is effected, and the proper effective length of the top rod 10 is maintained under all conditions of use, irrespective of variations in the thickness of the brake shoes.

To permit the quarter turn of the housings 10 and associated parts referred to, the rack bar 7, which is circular in cross-section, is provided with a rib 30, which travels in a groove 31, formed in the connecting portion 15^a which lies between the part 15 and 15 the sleeve 13.

As shown in Fig. 4 (to which the same reference numerals have been applied in so far as they are applicable), I provide for a construction in which either end of the top rod 20 may be disconnected for the purpose of replacing the worn-out shoes. In this construction, the rack bar 7^b is provided with a longitudinal opening which extends therethrough, and through this opening extends a part 7^a of 25 the top rod. This part 7^a is secured to the live truck lever 6 in the same manner as has hereinbefore been described for securing the rack bar 7 thereto. The other end of the rod 7^a is provided with threads 7^c, which are fitted 30 to internal threads cut adjacent the outer end of the longitudinal opening in the part 7^a. A suitable lock nut 7^e serves to hold the part or rod 7^a in proper position. In constructing the rack bar 7^b, I cast or form there- 35 on a flange 7^f, which contacts the auxiliary housing and prevents accidental withdrawal of the rack bar 7^b. The operation of the device is the same in each case.

It is to be understood that the invention is 40 not limited to the precise construction set forth, but that it includes within its purview whatever changes come fairly within either the terms or the spirit of the appended claims.

Having described my invention, what I 45 regard as new, and desire to secure by Letters Patent of the United States, is:

1. In a brake rigging, a two-piece top rod which constitutes a connection between a cylinder lever and a live truck lever, a part of 50 said rod being provided with a row of ratchet teeth, the other part of said rod carrying a housing which encloses said ratchet teeth, a sleeve in said housing, an auxiliary housing slidably secured to said other part of said rod, a telescoping sleeve thereon slidable on the 55 first mentioned sleeve, dogs in said housings which normally engage said ratchet teeth, and a stop against which said auxiliary housing abuts when the brakes are set.

60 2. In a brake rigging having cylinder levers, brake shoes, live truck levers, lower rods, two-piece top rods, and means to actuate the same, ratchet teeth formed on one part of the top rod, one end of which is pivotally secured 65 to the live truck lever, a housing fixedly se-

cured to the other part of the top rod, said ratchet teeth passing through said housing, a sleeve in said housing, an auxiliary housing slidably mounted on said other part of the top rod, a telescoping sleeve on said auxiliary housing which telescopes the first named sleeve, a spring which holds them normally separated, a dog in each housing which engages said teeth, and a permanent stop against which said auxiliary housing abuts when the brakes are set.

3. In a device of the character described, the combination with a brake rigging having cylinder levers, brake shoes, live levers, lower rods and two-piece top rods which connect 80 said cylinder levers and said live truck levers, one of said pieces having ratchet teeth thereon, the other being smooth, automatically operated means secured to said top rods which will shorten the same as the brake shoes wear, 85 said means comprising a fixed housing, an auxiliary housing, a pair of telescoping sleeves on said housing, a spring which normally holds them separated, means on said housing which engage and hold said rods, an upwardly extending portion on the auxiliary housing which forms a guide for the smooth piece of the top rod, one end of each two-piece top rod being pivotally secured to the cylinder lever and live truck lever respectively. 90

4. A structure as recited in claim 1, in combination with a spring in said sleeves, and tending to thrust them apart.

5. A structure as recited in claim 1, in combination with a well associated with each of said sleeves, a dog in said well, a spring in the well tending to thrust the dog into engagement with said ratchet teeth, and means tending to thrust the sleeves apart. 100

6. A structure as described in claim 3, in combination with a tubular rack fixedly mounted on one part of each top rod, the other part of said rod carrying a housing which encloses said tubular rack, a sleeve in said housing, an auxiliary housing slidably secured to said other part of said rod, a telescoping sleeve thereon slidable in the first mentioned sleeve, means tending to thrust the sleeves apart, spring-actuated dogs in said housings, and a stop for said auxiliary housing. 105
